UNITED STATES PATENT OFFICE.

CHARLES A. CRIQUI, OF BUFFALO, NEW YORK.

POWER-BOAT.

1,108,340.

Specification of Letters Patent. Patented Aug. 25, 1914.

Application filed March 28, 1912. Serial No. 686,717.

To all whom it may concern:

Be it known that I, CHARLES A. CRIQUI, a citizen of the United States, residing at Buffalo, in the county of Erie and State 5 of New York, have invented new and useful Improvements in Power-Boats, of which the following is a specification.

This invention relates to power-driven boats of the class having one or more tunnels which inclose the usual propellers.

In ordinary canal boats or barges, the propeller or propellers extend beyond the stern, but this construction is unsuitable on some of the recently-improved barge canals, 15 on account of the limited distance between locks which requires the propellers to be placed in tunnels under the boat.

The object of my invention is the provision of a portable and self-contained tunnel 20 or tunnel-structure, which may be conveniently applied to an ordinary existing canal-boat, barge or other craft at comparatively small expense and without the necessity of materially altering or rebuilding the boat, 25 and which is so constructed and fitted in the hull as to insure a water tight joint between these parts.

In the accompanying drawings: Figure 1 is a sectional elevation of an ordinary flat-bottomed boat equipped with the improved tunnel. Fig. 2 is a fragmentary transverse section on line 2—2, Fig. 1, on an enlarged scale. Fig. 3 is a detached perspective view of the tunnel.

35 Similar characters of reference indicate corresponding parts throughout the several views.

1 indicates the hull of the boat, 2 the propeller, 3 the propeller-shaft and 4 a gas 40 engine or other motor for driving the propeller-shaft in the customary manner.

5 indicates the tunnel which incloses the propeller and is a structure or element complete in itself and made separate from the hull. The tunnel is secured in an opening 45 of the proper form and size cut in the bottom of the boat. This tunnel may be constructed of sheet metal or other suitable material and in its preferred form comprises 50 side walls 6 connected by an arched top, the bottom and the rear end of the tunnel being open like an ordinary built-in tunnel. The highest portion 7 of this top is substantially 55 level or horizontal, while its remaining portions are inclined forwardly and rearwardly

therefrom, as shown at 8 and 9, respectively. At its base the tunnel is provided with an outwardly-projecting attaching flange 10 which extends around its front and along its sides to its rear end, this flange bearing 60 against the bottom of the hull and having holes for the passage of fastening bolts or screws 11. A suitable packing 12 is interposed between this flange and the hull to form a water-tight joint. Within the tunnel is a rear bearing 13 for the propeller shaft which is carried by suitable arms or brackets 14 secured to the inner side of the tunnel. 15 indicates a front bearing for said shaft mounted on the inclined front portion 8 of the tunnel. The high portion 7 of the tunnel is located opposite the propeller and contains a hand or man-hole through which the propeller and its shaft are accessible for clearing the same of weeds, 65 or other purposes. This hole is normally closed by a cover 16 clamped in place by an upright screw 17. This screw engages a threaded opening in a yoke 18 which is 70 removably interlocked with a stationary rim 19 surrounding said man-hole, preferably by bayonet joints 20, so that upon loosening the screw and partially turning the yoke, 75 the latter and the cover are released. A suitable water-tight hood or casing 21 preferably surrounds the man-hole. This hood is open at its upper end and is of sufficient height to extend above the water level when the boat is loaded, so that access may be 80 had to the submerged propeller after removing the cover 16 without flooding the boat. 85

My improved tunnel constitutes a complete and portable structure which can be manufactured separately from the hull of a boat and can be easily applied to an ordinary canal boat or similar flat-bottom craft by simply cutting a hole in its bottom to receive the tunnel which is readily bolted in place, as above described. As this conversion of an ordinary boat having no tunnel into a tunneled craft can be effected 90 without requiring any material change in its construction, the cost of the change including that of the improved tunnel is considerably less than would be the cost of rebuilding the boat with the usual built-in tunnel. By a relatively small outlay the improvement thus renders available on improved barge-canals, old or existing barges 95 which would otherwise be unserviceable or 100 105 110

require reconstruction involving a practically prohibitive expense.

By providing the tunnel with a base flange which bears against the underside of the hull, the tunnel can be conveniently introduced into the opening of the hull through the bottom thereof, avoiding the necessity of removing a portion of the deck and adjacent parts, which is required when the construction of the tunnel is such that it must be introduced through the top of the boat. This arrangement of the flange against the underside of the hull also insures a water tight joint between the parts inasmuch as the upward pressure of the water against the flange tends to maintain such a joint.

I claim as my invention:

The combination of the hull of a boat having an opening in its bottom, and a tunnel separate from the hull and arranged therein, said tunnel having at its base a projecting flange bearing against the underside of the hull and secured thereto, whereby the flanged tunnel may be introduced upwardly into said hull-opening through the bottom of the boat and said flange is exposed to the upward pressure of the water.

Witness my hand this 25th day of March, 1912.

CHARLES A. CRIQUI.
